JOHN BALDWIN ADAMS, OF CHRISTCHURCH, NEW ZEALAND.

LIFE-SAVING BUOY.

1,089,617.

Specification of Letters Patent. Patented Mar. 10, 1914.

Application filed December 12, 1913. Serial No. 806,180.

To all whom it may concern:

Be it known that I, JOHN BALDWIN ADAMS, a subject of the King of Great Britain, residing at 308 Armagh street, Christchurch, in the Dominion of New Zealand, have invented new and useful Improvements in Life-Saving Buoys, of which the following is a specification.

This invention relates to a life-saving buoy or float for use in saving people from drowning. Hitherto these have generally been made of cork. The weight of cork however, is such, that, to provide a float capable of efficiently supporting several persons, necessitates a somewhat bulky and cumbersome construction, while, owing to the high price of cork such construction would be expensive. Apart from this however the buoyancy depends upon the cellular structure of cork and experience has shown that in the course of time, and under the conditions to which such devices are subjected, deterioration of the cork takes place which results in the loss of such cellular structure, and consequently, of its buoyant properties. Hitherto it has been proposed, as a substitute for cork, to employ a padding of some light fibrous material inclosed in a water-proof envelop. Such construction however, although providing greater buoyancy bulk-for-bulk than cork and at a considerably lower cost, has proved unsatisfactory owing to the lack of rigidity in consequence of which such construction is liable to flexing under the strain that would be thrown upon it with the result that an injury to the envelop would occur and so impair the waterproof properties of the latter.

The objects of the present invention are therefore, firstly to provide a construction which will combine the qualities of great buoyancy and inexpensiveness of manufacture with such rigidity and imperviousness to water as to render it capable of use efficiently under the required conditions; secondly, to provide a device capable of use on ship-board, or by life-saving corps at the seaside, adapted to be conveniently towed out by one or more swimmers through surf breakers or a rough sea to the aid of any person in need of assistance and to provide an efficient means whereon such rescued persons may be supported and conveyed to safety; thirdly, to provide a unit which may be conveniently handled and thrown into the water where it may be assembled with other

similar units so as to provide a pontoon or raft which will serve to supplement the accommodation of the ships' boats.

In order that the nature of the invention and its construction may be fully understood, reference will now be made to the accompanying sheet of drawings in which:—

Figure 1.— is a view of the buoy as a whole, Fig. 2.— is a longitudinal section of the same showing its construction. Fig. 3.— illustrates in perspective the framework employed for strengthening the buoy, and, Fig. 4.— illustrates the buoy when being towed out by swimmers to render assistance.

The buoy is made of suitable size and approximately of torpedo-shape, being virtually cylindrical in form and tapering to a cone-point at each end. It is formed (as shown in Fig. 2) by means of a metallic rod 70 or rod of other rigid material 1. Surrounding the said rod 1 is arranged a padding 2 of kapoc or other light material which is hermetically inclosed by means of a water-proof envelop 3 of thin prepared canvas. 80 The said construction is arranged within a closely fitting framework of "eel-basket" formation as shown in Fig. 3, of metal or other suitable material and comprising a combination of longitudinal members or 85 staves 4 and circumferential members or ribs 5. Surrounding the said framework is a water-proof envelop 6 of thick prepared canvas which in turn is inclosed within an outer water-proof cover 7 also of thick canvas to which is applied a sufficient number 90 of paint layers to render it impervious to the action of water.

By the above described construction it will be seen that the outer skin 7 will, if intact, 95 serve to protect the whole of the interior from contact with the water. In the event of failure of such outer skin, however, due to mechanical injury as might be occasioned by contact with sharp objects or due to rotting of the fabric in consequence of continual exposure to the sun or repeated contact with water or moisture, the water after passing through the skin 7 would come in contact with the inner skin 6 and which 100 would effectually serve to protect the interior. Again in the event of both the skins 6 and 7 being penetrated as might take place in the event of the buoy being dashed violently against wreckage or projecting points 105 of rock, the water would still be prevented from contact with the padding 2 by the in-

nermost envelop 3, while the damaged skins 6 and 7 although rendered non-waterproof would, by reason of the fact that they are supported by the aforesaid framework, still 5 serve to afford protection to the envelop 3 from mechanical injury and thus enable the buoy to continue its function.

The construction of the framework is such that although as a whole the structure will 10 effectually resist any tendency on the part of the buoy to flexing under a strain, yet the individual members of which it is constituted will be sufficiently springy to withstand an impact without danger of break- 15 age or buckling. By this construction also the combined action of the rod 1 and the framework will serve to maintain the padding 2 in shape and position and thus prevent any undue strain from being thrown 20 upon the envelops 3, 6 and 7.

The buoy may be provided with the life-lines or loops of rope 8 for use in clinging to such buoy and which may be provided with rings, swing-buckles, or the like 9 for 25 the attachment of belts or other means placed upon the succored persons. Rings 10 or other means may also be provided at the extremities of the buoy, to one of which traces 11 may be attached to enable such 30 buoy to be towed out to the person in need of assistance, while to the ring or other means at the opposite end of such buoy, a line 12 may be attached for the purpose of 35 hauling such buoy with the succored persons back to safety. A pocket 13 may also be

provided to hold any stimulants or appliances likely to be required in rendering first aid. To cause it to float with the desired side normally upward, the buoy may be suitably weighted.

On account of its particular shape the buoy may be towed through the water with a minimum of resistance and through surf-breakers or a rough sea without danger of drowning any persons clinging or attached thereto, while such shape also affords a maximum of strength to the construction.

In cases of shipwreck a number of such buoys may be thrown into the water where they may be assembled in groups as required 50 and secured together side by side so as to provide rafts for the purpose of receiving and conveying passengers to safety.

I claim—

A device of the class described comprising in combination a rod surrounded by a padding of light fibrous material, a thin water-proof envelop hermetically inclosing said padding, a framework of longitudinal and circumferential members inclosing said envelop, and one or more outer protecting water-proof skins inclosing said construction, substantially as set forth.

In testimony whereof I have signed my name to this specification in the presence of 65 two subscribing witnesses.

JOHN BALDWIN ADAMS.
